WALTER P. FRISCH, OF ROCHESTER, NEW YORK

TIME-CONTROL MECHANISM

Application filed February 11, 1928. Serial No. 253,733.

The present invention relates to time control mechanisms. An object of this invention is to provide, in connection with a clock or timing mechanism, a simple and inexpensive mechanism which may be operated from one of the hand shafts of a clock without imposing upon the shaft a load of any great moment. Another object of the invention is to mount on one of the shafts of a clock a device which may be brought readily into connection with a rotary member having a common axis of turning with the shaft to impart from the shaft movement to the rotary member.

To these and other ends, the invention consists of certain parts and combinations of parts all of which will be hereinafter described: the novel features being pointed out in the appended claims.

In the drawings:

20 Fig. 1 is a front view of the clock or timing mechanism showing a portion of the door for the dial broken away;

25 Fig. 2 is an interior view of the mechanism with the rear face of the casing removed;

Fig. 3 is an enlarged horizontal section on the line 3—3, Fig. 1;

Fig. 4 is a section on the line 4—4, Fig. 3;

Fig. 5 is a section on the line 5—5, Fig. 3;

30 Fig. 6 is a section on the line 6—6, Fig. 3; and

Fig. 7 is an end elevation with an end broken away to show interior parts.

In the illustrated embodiment of the invention, 1 indicates a casing closed by a removable rear plate 2 and having therein a clock or timing mechanism 3 of any desirable construction supported on a supporting plate 4 held by spacing devices 5 in spaced relation 40 to the front wall of the casing. The clock or timing mechanism has a minute hand shaft 6 supporting the minute hand 7, and an hour hand shaft 8 supporting the hour hand 9, both hands being situated in front of the 45 front wall of the casing and covered, in this

instance, by a cover 10 provided with a glass front and hinged at 11 to the front wall so as to render said hands readily accessible. The front wall of the casing has, in this instance, an opening 12 in which is arranged an annular member provided with a dial 13 over which the hands 7 and 9 operate. The annular member, in this instance, is supported against turning on the supporting plate 4.

The mechanism to be operated comprises, 55 in this instance, a rotary member 14 mounted to turn about the axis of turning of the minute and the hour shaft 6 and 8 respectively and situated in rear of the central opening of the annular member. In this instance, this 60 rotary member 14 is in the form of a disk having a hollow shaft 15 extending rearwardly therefrom through a bearing 16 in the supporting plate 4, the hollow shaft 15 having a nut 17 at its inner end to cooperate with the 65 end of the bearing 16 in order to hold the rotary member to the bearing 15. The minute and hour shafts 6 and 8 extend through this hollow or tubular bearing 15 from the clock or timing mechanism to the minute and hour 70 hands 7 and 9 respectively operating over the dial 13.

Any suitable means may be employed for establishing driving connection between this 75 rotary member 14 and the timing mechanism. In this instance, connection is established between the hour hand shaft 8 and the rotary member 14 preferably through the hour hand 9. To this end, the hour hand may carry a connecting device, in this instance, in the form 80 of rearwardly extending teeth or prongs 18 adapted to be brought into engagement with interlocking means on the rotary member 14. This means on the rotary member comprises, in this instance, a ring of rubber or other 85 yielding material secured to the outer or front face of the rotary member 14 within the opening of the annular member. An annular rib 13^a may be provided about the opening of the annular dial carrying member in 90

order to limit the amount the projections on the hour hand are pressed in the yielding ring.

Suitable means may be employed for controlling the connection between the hour hand 9 and the rotary member 14. In this instance, this means may consist of one or more controlling devices adjustable about the axis of turning of the hour hand in a complete circle and engaging such hour hand to flex the latter inwardly adjacent its free end in order to force the projections 18 into the disk 19, thereby causing the rotary member 14 to turn with the hour hand, so long as the interlocking connection between the hour hand and the rotary member 14 is maintained. Each controller, in this instance, is in the form of an arm 20 having a free end portion 21 turned inwardly to engage the hour hand as the latter moves by the same. The arm 20 is mounted on a shiftable carrier 22 in the form of a headed screw which operates in an undercut way or guide 23 formed in the face of the annular member about the dial 13. Each arm 20 has the screw threaded portion of the carrier passed therethrough and a nut 24 engages the screw threaded portion and clamps the arm against the annular member. The cover 10 covers the guideway for the controllers as well as the inner ends of the controllers so that only the free ends of the controllers are visible. Each controller may be shifted to any position over the dial so as to cause the hour hand to be brought into connection with the rotary member 14 at any point in the travel of the hour hand over the dial 13.

With the end in view of preventing the shifting of the rotary member 14 accidentally when the said rotary member is not connected with the timing mechanism, a combined retaining and centering device may be employed comprising, in this instance, a spring arm 25 secured at one end at 26 to the plate 4 and having a ball 27 secured thereto and adapted to cooperate with the walls of any one of the pockets 28 formed in the rear face of the member 14 in equi-spaced relation concentric with the axis of turning of said member 14. This ball imposes sufficient resistance to the turning of the member 14 to prevent the accidental movement of the member 14 but it yields to permit the movement of the member 14 under the action of the timing mechanism, and centers the member 14.

The rotary member 14 may be employed for operating or controlling any suitable means or mechanism. In this instance, it operates a signalling device and controls an electrical circuit. This is effected by forming the member 14 with beveled gear teeth 29 which are engaged by a small beveled pinion 30 on a shaft 31 which is supported by pin bearings 32 at opposite ends adjustable 60 on brackets 33 extending from the support-

ing plate 4. The shaft 31 is radial to the axis of turning of the member 14 and lies in rear of the front wall of the casing 1. It may carry a drum 34 which projects through an opening 35 in the front wall of the casing and is provided with undercut faces 36 receiving movable memorandum cards 37. The shaft 31 may also support a disk 38 of insulating material arranged at one end of the drum 34 and having a contact embedded therein and provided with a plurality of radially arranged arms 39 connected with a conductor sleeve 40 surrounding the shaft 31. This conductor sleeve is in turn engaged by a yielding contact arm 41 secured to a binding post 42. Another binding post 43 has a yielding contact arm 44 secured thereto and arranged to engage the face of the disk 38 so as to successfully engage the contact arms 39. Any number of these contact arms 39 may be employed so that the arm 44 will be engaged any desired number of times with each rotation of the insulating disk 38. The switch thus formed may be employed for controlling any suitable electric appliance connected to the binding posts 42 and 43.

With the end in view of operating a mechanical alarm with the operation of the member 14, an alarm or signal bell 45 may be provided to be engaged by a striker 46 which is controlled in the usual manner by a separate spring in the clock mechanism. Moving with the striker arm is a controlling arm 47, the end of which cooperates with one end of the drum 34 so as to hold the alarm or signalling mechanism against action. This drum however has in its end a plurality of slots or openings 48 one of which after the drum rotates becomes positioned adjacent the end of the arm 47 and permits such end to drop therein and cause the alarm or signalling mechanism to function in the usual manner. If desired adjustable blocks 49 movable in the slots 48 by screws 50 may be employed to prevent the alarm from acting when the slots are reached, so that the alarm need not act on each movement of the drum.

The operation of the invention will be understood from the foregoing but it may be summarized as follows: The rotary member 14 with the parts connected thereto normally lies in a stationary condition. Assume that it is desired to operate any desired mechanism, one of the controllers 20 of which there may be any desired number is adjusted over the dial 13 to the time at which it is desired the member 14 to turn. When the hour hand 9 reaches the inwardly turned end 21 of a controller 20, said hand is flexed laterally so that its projection 18 is forced into interlocking connection with the yielding disk 19 whereby the disk with the rotary member 14 are caused to turn together for a short period. During this turning, the shaft 31 is turned, 120 125 130

thus not only turning the drum 34 but also the rotary contact arms 39 to close the switch. At the same time, the controlling arm 47 drops in one of the slots 48 and causes the alarm to operate. The parts stay in these positions until the rotary member 14 is again turned through the flexing of the hour hand 9 into engagement with the disk 19. After each flexing of the hour hand by one of the controllers 20, it automatically passes out of engagement with the disk 19 when the hour hand has passed beyond the controller 20.

What I claim as my invention and desire to secure by Letters Patent is:

15 1. A time controlled mechanism comprising a clock mechanism having its hour and minute shafts coaxially arranged, a member mounted to turn about the common axis of said shafts, and two cooperating devices, one 20 on the rotary member turning with the latter and the other making complete rotations with one of the shafts and connectible with the device on the rotary member so that the two devices turn together and stationary 25 means engaging the part turning with the shaft for effecting connection between the rotary member and said part.

2. A time controlled mechanism comprising a clock mechanism having its hour and 30 minute shafts coaxially arranged, a member mounted to turn about the common axis of said shafts, means extending about and in spaced relation to the axis of the member, and means carried by one of said shafts in 35 spaced relation to the axis of the shafts and movable into engagement with the means on the rotary member to cause the rotary member to turn with said shaft and stationary means engaging the part turning with the 40 shaft for effecting connection between the rotary member and said part.

3. A time controlled mechanism comprising a clock control mechanism having its minute and hour shafts axially arranged, a 45 a minute and an hour hand connected respectively to said shafts, a rotary member mounted to turn about the common axis of the shafts, means arranged on said rotary member concentric with and in spaced relation to the axis of said member, and means 50 carried by one of the hands to turn therewith in a complete circle and movable into engagement with the means on the rotary member to cause the rotary member to turn with the said hand and stationary means engaging the part turning with the shaft for effecting connection between the rotary member and said part.

4. A time controlled mechanism comprising a clock mechanism having its hour and minute shafts coaxially arranged, a member mounted to turn about the common axis of said shafts, means arranged on said rotary member concentric with and in spaced relation to the axis of said member, a flexible

arm secured to one of the shafts, and a device carried by said arm in spaced relation to the axis of said shaft and moving into engagement with the means on the rotary member to cause the latter to turn with the arm.

5. A time controlled mechanism comprising a clock mechanism having its hour and minute shafts coaxially arranged, a member mounted to turn about the common axis of said shafts, means arranged on said rotary member concentric with and in spaced relation to the axis of said member, a flexible hand secured to one of said shafts, and means carried by said hand in spaced relation to the axis of its shaft and movable into engagement with the means on the rotary member to cause the latter to turn with the hand and stationary means for flexing said hand to cause said device to engage said member to cause the member to turn with the hand.

6. A time controlled mechanism comprising a clock mechanism having its hour and minute shafts coaxially arranged, a member mounted to turn about the common axis of said shafts, yielding means arranged on said member about the axis of the latter, a flexible arm secured to one of the shafts, and a projecting device carried by said arm in spaced relation to the axis of said shaft and moving on the flexing of the arm into engagement with the yielding means of the rotary member to cause the latter to turn with the arm.

7. A time controlled mechanism comprising a clock mechanism having its hour and minute shafts coaxially arranged, a member mounted to turn about the common axis, two cooperating devices, one on the rotary member turning with the latter and the other connected to one of the shafts to make complete rotations with the latter, a controller for cooperating with said last mentioned cooperating device to move the latter into engagement with the first mentioned device, and means for adjusting said controller in a complete circle about the coaxially arranged shafts.

8. A time controlled mechanism comprising a clock mechanism having its hour and minute shafts coaxially arranged, a disk like member mounted to turn about the common axis of said shaft, means arranged on said rotary disk like member concentric with and in spaced relation to the axis of said member, a flexible hand secured to one of said shafts and turning therewith, a device carried by said hand and movable upon the flexing of said hand into and out of engagement with said concentric means on the rotary member, and a controller adjustable in a complete circle about the axis of rotation of the hand and adapted to engage the latter to flex the same so as to bring the device thereon into engagement with the concentric means on the rotary member.

9. A time controlled mechanism comprising a clock mechanism having its hour and minute shafts coaxially arranged, a flexible hand secured to one of said shafts and turning therewith, movable means arranged to be engaged by said flexible hand in any position to which the hand may be turned, and a controller adjustable in a complete circle about the axis of rotation of the hand and adapted to engage the latter to flex the same so as to bring said hand into engagement with the movable means.
